United States Patent Office

Des. 202,981
Patented Nov. 23, 1965

202,981

BUILDING

Robert H. Power, Nut Tree, Calif., assignor to
Nut Tree, a limited partnership

Filed Aug. 14, 1964, Ser. No. 81,292

Term of patent 14 years

(Cl. D13—1)

FIG. 1

FIG. 3

FIG. 4

FIG. 5

FIGURE 1 is a top plan view of the building;
FIGURE 2 is a front elevation of the building;
FIGURE 3 is a side elevation of the building when
looking at the right hand side of FIGURE 1;
FIGURE 4 is another side elevation of the building
when looking at the left hand side of FIGURE 1; and
FIGURE 5 is a rear elevation of the building.
I claim:
The ornamental design for a building, substantially
as shown.
